UNITED STATES PATENT OFFICE.

JOHN J. RUDDICK, OF NEWTON, MASSACHUSETTS, ASSIGNOR TO UNITED STATES.
ELECTRIC SIGNAL COMPANY, A CORPORATION OF MASSACHUSETTS.

BLOCK-SIGNAL SYSTEM.

1,278,509.

Specification of Letters Patent. Patented Sept. 10, 1918.

Application filed March 19, 1913. Serial No. 755,322.

To all whom it may concern:

Be it known that I, JOHN J. RUDDICK, a citizen of the United States, residing at Newton, county of Middlesex, State of Massachusetts, have invented an Improvement 5 in Block-Signal Systems, of which the following description, in connection with the accompanying drawing, is a specification, like characters on the drawing representing 10 like parts.

This invention relates to block signal systems such as are adapted for use on either steam or electric railways for controlling the movements of trains or cars, and especially to block signal systems which are provided with counting-in-and-out devices so 15 that a plurality of cars may follow each other into the block in the same direction without disturbing the signals.

One of the objects of the invention is to 20 provide an electrically-operated block signal system which is especially adapted for use in connection with semaphores, and which is so arranged that under normal conditions the semaphores at each end of the 25 block are in vertical or "safety" position, but whenever a car enters the block at one end the semaphore at the opposite end of the block will be dropped into horizontal 30 or "danger" position, while the semaphore at the entering end of the block will be dropped into a 45° or "caution" position.

A further object of the invention is to 35 provide a signal system of this type which is so constructed that whenever a second car enters the block following the first car, said second car will cause the semaphore at the entering end of the block to have a momentary movement from its 45° to its vertical 40 position and back again which will indicate to the motorman of said second car that the counting-in-and-out device has operated properly.

A further object of the invention is to 45 provide a signal system of this type wherein if a second car follows a first car into the block and thus operates the counting-in-and-out device at the entering end of the block, and then said second car backs out 50 of the entering end of the block, the counting-in-and-out device as said entering end of the block will be restored to the position it was left in by the first named car without, however, disturbing in any way the signals which have been set.

A further object of the invention is to provide a signal system of this type wherein if a car runs by a stop or danger signal set against it and enters the block and then backs out of the block, said car will operate 60 the counting-in-and-out device to cancel the registration made when it passed the signal and entered the block without, however, disturbing any of the signals that have been previously set.

A still further object of the invention is to provide a block signal system capable of accomplishing these various results but having only two wires extending the length of the block.

Other objects of the invention are to provide a novel interlocking connection between the various relays of the system which make the system certain in its action under all conditions.

I will first describe one embodiment of my invention and then point out the novel features thereof in the appended claims.

Referring to the drawings, Figures 1 and 2 show a complete system embodying my invention, Fig. 1 showing the construction at one end of a block, and Fig. 2 that at the opposite end. It will be observed that Figs. 1 and 2 thus form in effect a continuation of each other and illustrate one complete 85 block;

Fig. 3 is a fragmentary perspective view of the counting-in-and-out device.

I have shown my invention herein as it would be applied to an electric railway, in 90 which case the current for operating the signals is taken from the trolley wire or feed conductor which is designated generally by 1. The track on which the car is run is shown at 2, and this constitutes the return or ground for the various circuits.

My signal system comprises a normally-closed local semaphore circuit at each end of the block which directly controls the semaphores, a signal-actuating circuit which extends the length of the block and has therein relays for controlling the local semaphore circuits at both ends of the block, local setting and restoring circuits at each end of the block for controlling the signal-actuating circuit, a controlling circuit which also extends the length of the block and which coöperates with the other circuits in the accomplishment of the above objects, and track relay circuits at each end 110

of the block by which the signaling operations are initiated.

The signal-actuating circuit is provided at each end of the block with a ground connection and with a feed connection, and the controlling circuit is also provided at each end of the block with a ground connection and a feed connection. The construction is such that normally when the block is open 5 the signal-actuating circuit is connected at one end of the block to its feed connection and at the other end of the block to its ground connection so that said signal-actuating circuit is normally closed. Said signal-actuating circuit has therein at each end of the block a local relay which controls the corresponding local semaphore circuit, said semaphore circuits being normally closed. The current flowing in these local semaphore circuits holds the two semaphores, one at each 10 end of the block, in their safety position. The setting of the signal involves the breaking of the signal-actuating circuit and the consequent deenergizing of the local relays 15 therein with the resultant opening of the local semaphore circuits. The opening and closing of the signal-actuating circuit is controlled by a counting-in-and-out device which is operated by the setting and restoring circuits of the track relay whenever a 20 car enters or leaves the block.

Before entering into a detailed description of the signaling device and its operation, I will first trace out generally the principal circuits, as above outlined.

The track relays, one at each end of the block, are designated generally by 3 and 4, respectively, and they are both alike and have substantially the construction illustrated in 25 my patent No. 1,069,027, dated July 29, 1913. Since these track relays do not form part of the present invention, it will not be necessary to describe them in detail, but it will be sufficient to say that each track relay comprises a 30 setting magnet and a restoring magnet 5 and 6, respectively, both of which are differentially wound with the windings in series and the windings of both connected to the ground connection 13. Each track relay circuit has 35 a feed connection 9 that takes current from the trolley wire 1 through the main feed arm 12 which also supplies current to some of the other circuits presently to be described. Each track relay feed connection 9 is shown as 40 having therein a lamp 10 to illuminate the spectacle of the semaphore 24, there being one such semaphore at each end of the block.

Each track relay magnet 5, 6 has connected thereto between the two windings thereof a 45 shunt connection, said shunt connections for the magnet being designated 7 and 8, respectively, and leading to insulated rail sections 10 and 90. These shunt connections are normally inactive because they are connected 50 with the insulated rail sections, but whenever

a car passes onto either insulated section, then the current will flow through the corresponding shunt connection to the ground, thus short-circuiting one of the differential windings of the corresponding relay magnet 70 whereby said magnet is rendered operative. For a more complete description of the operation of the track relay reference may be had to said above-mentioned patent.

The magnets 5 and 6 of each track relay 75 control setting and restoring circuits which are normally open, but which are closed whenever the relays are operated by a car passing onto either one of the insulated track sections. The setting circuit for each 80 relay is designated 14 and it connects at one end with the trolley wire at 15 through a feed connection 140 and leads to contacts 16 controlled by the track relay setting magnet 5, thence to a setting magnet 17 which operates the counting-in-and-out device designated generally by 18, and thence to the ground through the main ground connection 19. The restoring circuit for each track 85 relay is designated 20 and it takes current from the feed connection 140 and leads to the contacts 21 controlled by the track relay restoring magnet 6, and thence to the restoring relay 22 and to the main ground connection 19. Both of the setting and restoring 90 circuits are normally open, and one or the other is closed by its magnet whenever a car passes over the insulated rail sections 95 and 10, that depending on the direction in which the car moves, as will be obvious, and all as fully set forth in my said Patent No. 1,069,027.

The local semaphore circuit at each end of the block is designated 23 and in order to distinguish it readily, I have shown it in 105 heavy dot and dash lines. It directly controls the semaphore 24. These semaphores are shown as pivoted at 25, and each has connected thereto the core 26 of a semaphore-operating magnet 27 which is arranged so that so long as the magnet is energized the semaphore is held in vertical position. Whenever the magnet 27 is deenergized, however, the semaphore will fall by gravity. The local semaphore circuit 23 110 connects with the main feed connection 12 and leads to the semaphore-controlling magnet 27 and thence to contacts 30 of a local relay 31 which is in the signal-actuating circuit, and thence to the main ground connection 19.

The signal-actuating circuit which extends the length of the block has a ground and a feed connection at each end of the block, as stated above. This signal-actuating circuit is designated 32 and it is shown in heavy solid lines. It includes contacts 33 controlled by the restoring relay 22 at each end of the block and leads to the terminal 55 of each counting-in-and-out device 18. 130

The feed connection for the signal-actuating circuit at each end of the block is designated 34 and leads from the main feed connection 12 to a point 340 where it connects to a terminal connection 99 of the corresponding counting-in-and-out device. This terminal connection 99 leads to a terminal 53 of the counting-in-and-out device 18 and includes the local relay 31. The ground connection 10 for the signal-actuating circuit at each end thereof is designated 35 and leads from the terminal 52 of the counting-in-and-out device 18 to the ground connection 19, and it includes the restoring magnet 36 that restores the counting-in-and-out device 18 and the contacts 37 controlled by a determining relay 38. The controlling circuit which also extends the length of the block is designated by 39 and it is shown in light arrow lines. It leads from the terminal 54 of one counting-in-and-out device 18 to the terminal 54 of the other counting-in-and-out device and includes contacts 40 controlled by the restoring relay 22 and the determining relay 38. The feed connection at each end of the block for the controlling circuit is designated 41 and leads from the main feed connection 12 to the terminal 57 of the counting-in-and-out device and includes the magnet 42 of the alternating relay 43, to be presently described. The ground connection for the controlling circuit at each end of the block is designated 44 and leads from the terminal 56 of the counting-in-and-out device 18 to the ground connection 35 of the signal-actuating circuit and includes the magnet 46 of the alternating relay.

The counting-in-and-out device may have any suitable construction adapted to perform the required functions. That herein shown comprises two cylinders 47, 48, each having a ratchet wheel 49 associated therewith which is adapted to be actuated by a pawl, said pawls being designated 50 and 51, respectively. The pawl 50 is actuated by the setting magnet 17 and the pawl 51 is actuated by the restoring magnet 36. The cylinder 47 is provided with an annular contact strip or terminal 52 with which the ground connection 35 of the signaling circuit is connected, an annular contact strip or terminal 53 with which the terminal connection 99 of the signal-actuating circuit is connected; and an annular contact strip or terminal 54 with which the controlling circuit 39 connects. The cylinder 48 has an annular contact or terminal 55 with which the signal-actuating circuit 32 connects; a terminal contact 56 from which the ground connection 44 of the controlling circuit 39 leads, and another annular contact terminal 57 from which the feed connection 41 of the controlling circuit 39 leads. The cylinder 47 is provided with a contact finger 58 electrically connected with the terminal 54

and adapted, when the parts are in normal position, to bear against a narrow contact 59 on the cylinder 48 which is electrically connected to the contact strip 57 by the wire 60. Since the contact finger 58 is electrically connected with the contact strip 54, it follows that when the parts are in normal position, as shown, said finger 58, contact 59 and connection 60 constitute an electrical connection between the controlling circuit 39 and its feed connection 41. The cylinder 48 carries a finger 61 which is electrically connected by a wire 62 with the contact strip 55, and when the parts are in normal position said finger has engagement with the contact 63 which is connected with the terminal strip 53 to which the terminal connection 99 of the signal-actuating circuit 32 is connected. Thus under normal conditions the terminal 55, wire 62, contacts 61, 63, terminal 53 and terminal connection 99 furnish the means for electrically connecting the signal-actuating circuit 32 with its feed connection 34 through terminal 99. The cylinder 47 is also provided with an elongated contact 64 adapted to be engaged by the finger 61 when the two cylinders are turned relative to each other, the contact 64 being connected electrically with the terminal 52 from which leads the ground connection 35 of the signal-actuating circuit. The cylinder 48 is also provided with an elongated contact 65 adapted to be engaged by the finger 58 when the two cylinders are turned relative to each other, said contact 65 being electrically connected with the terminal 56 to which is connected the ground connection 44 for the controlling circuit.

It will thus be seen that under normal conditions the counting-in-and-out device 18 at each end of the block furnishes an electrical connection between the signal-actuating circuit 32 and its terminal connection 99, and between the controlling circuit 39 and its feed connection 41.

The terminal connection 99 will be connected either to the feed connection 34 for the signal-actuating circuit, or to the ground, that depending on the position of the alternating relay 43.

Each alternating relay comprises the pivoted switch arm 100 which is moved in one direction or the other by the magnets 46 and 42, and which carries a contact 101 adapted to bridge either the contacts 102 in the feed connection 34 of the signal-actuating circuit 32, or the contacts 103 in a ground connection 104 that is shown as leading to the main ground connection 19, that depending on the position which said switch arm occupies. The purpose of these alternating relays is to make the signal system operable from either end of the block by a car going in either direction, all as will be more fully hereinafter described.

Under normal conditions when the block is clear, the alternating relay at one end of the block closes contacts 102 of the feed connection 34 and that at the other end of the block 5 closes the contacts 103 in the ground connection 104. It will thus be seen that under such normal conditions the terminal connection 99 of the signal-actuating circuit 32 at one end of the block is connected 10 with the feed connection 34 through the alternating relay, and at the other end of the block the terminal connection 99 is connected with the ground connection 104 through the other alternating 15 relay, so that the signal-actuating circuit is energized and the complete current path therethrough is as follows: Main feed connection 12 in Fig. 1; feed connection 34 including contacts 102 of the alternating relay 20 43; terminal connection 99 including local relay 31; terminal 53, contacts 63, 61 and terminal 55 of the counting-in-and-out device; signal-actuating circuit 32 to the signal box at the opposite end of the block and 25 including contacts 33 of the restoring relays at both ends of the block; terminals 55, wire 62, contacts 61, 63, terminal 53, and terminal connection 99 of the other counting-in-and-out device; and ground connections 30 104 (including its contacts 103 which are closed by the alternating relay) and 19. Current will thus flow through said signal-actuating circuit and through the local relays 31 at both ends of the block thereby 35 maintaining them energized and their armatures bridging the contacts 30 in the local semaphore circuits.

The controlling circuit, under normal conditions, is connected with the feed at 40 both ends of the block and is, therefore, inactive. Its connections are as follows: Main feed connection 12, feed connection 41; terminal 57, wire 60, contacts 59, 58 and terminal 54 of one counting-in-and-out device 45 18; controlling circuit 39 to the other counting-in-and-out device; terminal 54, contacts 58, 59, wire 60 and terminal 57 of said other counting-in-and-out device; feed connection 41; and main feed connection 12.

The local semaphore circuit 23 at each end of the block is normally maintained closed by the energized local relay 31 and the current path therethrough is as follows: 55 Main feed connection 12; wire 23 including semaphore-operating magnet 27, and contacts 30 that are closed by the armature of the local relay; and ground connection 19.

It will thus be seen that under normal 60 conditions when the block is clear, the closed signal-actuating circuit maintains the local relays 31 energized and thus maintains the local semaphore circuits 23 closed at contacts 30 at both ends of the block whereby 65 both magnets 27 are energized so that both

semaphores will be held in vertical or "safety" position.

The operation of setting the signals consists in opening the signal-actuating circuit 32 thereby deenergizing the local relays 31 at both ends of the block and opening both local-semaphore circuits at the contacts 30 with the result that both semaphore-actuating magnets 27 become deenergized, thus permitting the semaphores to fall by 75 gravity.

In order to give a better understanding of the invention I will describe how the system operates first, when a car enters the block at one end, and, second, when a car leaves 80 the block at the opposite end, third, when a car enters the block at one end and then backs out at said end, fourth when a second car enters the block following a first car, and, fifth, when a car runs by a stop signal 85 set against it and enters the block and then backs out.

It will be remembered that under normal conditions the signal-actuating circuit 32 is connected to the feed at one end of the block 90 and is connected to the ground at the opposite end while the controlling circuit 39 is connected to the feed at both ends. It will also be understood that since the signal-actuating circuit is normally closed the magnets of the local relays 31 therein are energized with the result that the armatures thereof hold the local semaphore circuits 23 closed at the contacts 30, and, therefore, that the semaphore-controlling magnets 27 at 100 both ends of the block are energized, thus holding the semaphores 24 in their vertical or "safety" position.

When a car enters a clear block the following operations take place:

Assuming that the car is traveling from left to right, then when said car enters the left hand end of the block and passes onto the insulated rail section 90, the track relay 3 is actuated to close the setting circuit 110 14 at the contacts 16. This setting circuit, which may be traced as follows in Fig. 1: feed connection 140, wire 14, contacts 16, setting magnet 17, and ground connection 19, thus includes the setting magnet 17, and as soon as said circuit is closed the magnet 17 is energized thereby operating through the pawl 50 and ratchet 49 to advance the cylinder 47 one step. The turning of the cylinder 47 relative to the cylinder 48 carries the contact fingers 58 and 61 onto the elongated contacts 63 and 64, respectively, thus connecting the signal-actuating circuit 32 at the entrance end of the block with its ground connection 35 and connecting the controlling circuit 39 at the entering end of the block with its ground connection 44. The signal-actuating circuit is thus disconnected from the feed and therefore becomes inactive, with the result that the local re- 125 130

lays 31 at both ends of the block become de-energized, so that their armatures drop away from the contacts 30 in the local semaphore circuits 23 and into engagement with the contacts 68 in the ground connections 35. Said signal-actuating circuit is now connected at both ends with the ground. As soon as the relays 31 are deenergized, both local semaphore circuits 23 are opened, and the 5 semaphore-actuating magnets 27 therein become deenergized, thus permitting the semaphores 24 at both ends of the block to fall by gravity. At the exit end of the block the semaphore falls to horizontal position, but 10 at the entering end of the block it only falls to a 45° position, as seen in dotted lines Fig. 1, it being held in such position by a stop member 69 that is normally inactive but is thrown at this time into position to engage 15 the semaphore and hold it at its 45° position. This stop 69 is in the nature of a pivoted arm which is controlled by a magnet 70 and there is such a stop 69 for each semaphore, but means are provided whereby only 20 the stop at that end of the block at which the car enters will be rendered operative, as will be presently described.

The stepping forward of the cylinder 47 of the counting-in-and-out device operates 25 to connect the controlling circuit 39 (which it will be remembered is normally connected at both ends to the feed) to its ground connection 44 whereby said circuit will be energized and current will flow therein from 30 the exit end of the block back to the ground at the entrance end of the block through the following current path: main feed connection 12 in Fig. 2, feed connection 41 including magnet 42 of the alternating relay; terminal 57, wire 60, contacts 59, 58, and terminal 54 of the counting-in-and-out device; controlling circuit 39 to the counting-in-and-out device at the opposite end of the block; terminal 54, contacts 58, 65, (it being remembered that the cylinder 47 of this last-named counting-in-and-out device has been advanced one step to bring the contact 58 onto the contact 65) and terminal 56 of said counting-in-and-out device; ground connection 44 which includes the magnet 46 of the alternating relay; and ground connection 35 to the main ground connection 19. The ground connection 35 includes the magnet 70 for the stop 69, and, therefore, when the 40 controlling circuit is thus energized the magnet 70 is operated to bring the stop 69 at the entering end of the block into the dotted line position, in which position it holds the semaphore in the 45° or "permissive" 45 position. It will be noted that the magnet 70 is in the ground connection 35, and, therefore, will be operated only when said ground connection is energized. It will further be noted that it is always the ground connection of the controlling circuit at that

end of the block at which the car enters which is energized, so that the semaphore at the entering end of the block only will be stopped in its 45° position.

I further call attention to the fact that when a car has entered the block as above described and the controlling circuit is energized the current in said controlling circuit will flow through the magnet 42 of the alternating relay at the further end of the block and through the magnet 46 of the alternating relay at the entering end of the block, and said controlling circuit, therefore, constitutes means for holding the alternating relays in the position shown in the drawings and which is necessary for the proper operation of the system.

The controlling circuit has therein the determining relays 38 and when the controlling circuit is energized these relays become energized and their armatures are lifted thereby opening the ground connections 35 at the contacts 37 and closing the pairs of contacts 71 and 72.

So long as a car which has thus entered the block remains in the block the above conditions are maintained.

When the car passes out of the block at the exit end the signals will be re-set to safety position by the following sequence of operations:

When the car passes onto the insulated rail section 10 in Fig. 2 the shunt circuit 8 is completed, thus energizing the track-relay-restoring magnet 6 with the result that the restoring circuit 20 will be closed at the contacts 21. The current path through the restoring circuit when thus closed may be traced as follows: feed connection 140, wire 20 including contacts 21 and restoring relay 22 to the ground connection 19. The restoring relay 22 at the exit end of the block thus becomes energized and its armature is lifted thereby opening both the signal-actuating circuit and the controlling circuit at the contacts 33 and 40 and closing the pairs of contacts 82 and 83. The closing of the contacts 82 will form a connection between the signal-actuating circuit 32 at the end of the block and the feed through the following current path: main feed connection 12, track relay feed connection 9 to contacts 82, thence through wire 74 to contacts 71 which are closed by the armature of the determining relay 38, thence through wires 75, 76, to contacts 77 which are closed by the alternating relay 43, thence through wire 78 to the signal-actuating circuit 32, thence to the switch box at the entering end of the block and to the terminal 55 at the counting-in-and-out device on the entering end of the block (it being remembered that the contacts 33 are closed at this time), thence through wire 62, contacts 61, 64 and terminal 52 of said counting-in-and-out device, 130

thence through ground connection 35 including contacts 68 and 37 which are closed, and also including the restoring magnet 36 to the ground connection 19. The restoring magnet 36 at the entering end of the block thus becomes energized thereby to advance the cylinder 48 one step, thus bringing said cylinder back into its normal position relative to the cylinder 47 and restoring the signal-actuating and controlling circuits to the normal conditions which they occupied before the car entered the block. It will thus be seen that the counting-in-and-out device which was stepped forward one step at the entering end of the block when the car entered said block will be restored to its normal position by a car leaving the block and by means of current which is sent through the signal-actuating circuit 32.

20 While I have described above the operation of my system when a car enters the block from the left-hand end and passes through the block traveling from left to right, I would state that the same sequence 25 of operations will transpire if a car enters a block from the right hand end and travels through it from right to left.

When a car enters the block from either end and sets the signals, as above described, 30 and then backs out of the entering end the signals will be restored to their normal position as follows:

It will be remembered that when the car has entered the block the signal-actuating 35 circuit 32 has been deenergized and the local relays 31 both deenergized, so that the armatures close the contacts 68. It will also be remembered that the controlling circuit 39 is closed and that the determining 40 relays 38 are energized so that their armatures close the contacts 71 and 72. Assuming that the car has entered the block from the left-hand end, then when said car backs off from the block at its entering end and passes onto 45 the insulated rail section 10, the shunt circuit 8 is closed, thus energizing the track-relay-restoring magnet 6 in Fig. 1 and closing the contacts 21 in the restoring circuit 20. This restoring circuit includes the restoring magnet 22 and may be traced as follows:

Feed connection 140, wire 20 including contacts 21 and restoring relay 22 and main ground connection 19. The restoring relay 55 22 thus becomes energized and its armature is lifted, thus opening the contacts 33 and 40 in the signal-actuating circuit 32 and controlling circuit 39, and closing the contacts 82 and 83. The opening of the controlling 60 circuit deenergizes the determining relays 38 therein so that their armatures tend to fall, but in order to carry out the desired operation it is necessary that the armature of the determining relay at that end of the 65 block at which the car is backing out should

remain elevated. I have accordingly provided means whereby whenever the restoring relay is energized its armature will lock that of the determining relay from movement. The construction herein employed for this purpose comprises a pivoted locking member 151 which bears against the inclined end 152 of the armature of the restoring relay 22, and which is provided with a finger 153 which is carried into the path of an extension 154 on the armature of the determining relay 38 when said locking member is moved by the inclined extension 152. Under the conditions above described which arise when a car backs off from the block, the energizing of the restoring relay 22 causes its armature to be elevated, and during the upward movement of the armature the inclined end 152 thereof acts on the locking member 151 and throws the finger beneath the extension 154 on the armature of the determining relay, thereby locking said armature in its elevated position. Hence when the controlling circuit 39, through which the determining relay is energized, is opened at the contacts 40, 90 the armature of said determining relay is still held against the contacts 71. There will, therefore, be established a current path from the main feed connection 12 as follows:

95 Main feed connection 12, wire 9, contacts 82, wire 74 to contacts 71, which, it will be remembered, are held closed by the armature of the determining relay 38 which is locked by the locking member 151, wire 75, 83 to contacts 85 which are closed by the alternating relay, wire 86 to the signal-actuating circuit 32 to the terminal 55 of the counting-in-and-out device; wire 62, contacts 61, 64, and terminal 52 of said counting-in-and-out device; ground connection 35 including contacts 68 which are now closed by the deenergized local relay 31, wire 87, including the contacts 83 which are now closed by the energized restoring relay 22; ground connection 35 and restoring magnet 36 to the main ground connection 19. The restoring magnet 36 thus becomes energized and the pawl 51 is given an impulse to turn the cylinder 48 thereby to bring it back into its normal position relative to the cylinder 47. The signal-actuating circuit 32 and its connections, and the controlling circuit 39 and its connections, are thus restored to their normal condition and the signal-actuating circuit will be closed, thus energizing the local relays 31 and the armatures of the latter will be lifted to close the contacts 30 in the local semaphore circuits, thus causing the semaphore magnets 27 to be energized 125 whereby the signals are brought into their vertical or "safety" position.

I will preferably construct each restoring pawl 51 so that the energizing of the restoring magnet will merely cause it to click over 130

the ratchet wheel 49, and so that when the magnet is deenergized the pawl will be actuated by a spring 154 thereby to turn the ratchet. With such a construction the cylinder 48 is not actually restored to its normal position until after the car has passed completely off from the insulated rail section 10.

When a succession of cars pass into the block one behind the other all going in the same direction, each car as it passes over the insulated rail section 90 will actuate the track relay and thus give the setting magnet 17 an impulse to step the cylinder 47 forward one step. Such forward movements of said cylinder, however, do not affect the ground connection between the controlling and signal-actuating circuits because the contacts 58 and 61 are on the elongated contacts 65 and 64.

Each time that the cylinder 47 is moved forward one step the semaphore 24 at the entering end of the block is given a momentary movement into its vertical position and back to its 45° position again, thus indicating to the motorman that the counting-in-and-out device has actuated properly. The means for accomplishing this is as follows:

The cylinder 47 has associated therewith a series of teeth 87 adapted to engage the end of a lever 88 pivoted at 89. Said lever carries at its upper end a contact 91 adapted to close normally open contacts 92 in the ground connection 93 leading from the semaphore circuit 23, and including contacts 94 of the alternating relay. Whenever the cylinder 47 is advanced one step one of the teeth 87 thereof will by its engagement with the lower end of the lever 88 swing said lever to momentarily close the contacts 92, thus closing the return connection 93 so that current will flow from feed connection 12 through circuit 23 and the magnet 27 and bring the signal back to its vertical position. Situated beneath the magnet 27 is a locking member 95 pivoted at 96 and adapted to be engaged by the lower end of the core 26 when the semaphore is in its vertical position. This locking member normally rests on the lever 88 and is provided with a locking shoulder 97 which engages behind the lever 88 when the latter is swung forwardly to close the contacts 92, thus locking the lever in such position and holding the ground connection 93 closed. Whenever the signal is returned to its vertical position, however, the core 26 will engage the locking member 95 and release it from its locking engagement with the lever 88, thus permitting the lever to be returned to its normal position by a spring 98.

Each time that a car follows another car into the block the last-above described operations are repeated and the semaphore 24 at the entering end of the block is given its

momentary impulse, thus indicating that the counting-in-and-out device has worked properly.

If a car runs by a signal which has been set against it, as, for instance, if a car enters the block from the left hand end and sets the signal to "danger" at the right end of the block, and then another car coming from the right runs by said danger signal and enters the block, said second car will actuate the counting-in-and-out device at said end of the block through the track relay circuits, as above described. My invention provides means whereby said car which has over-run its signal may back out of the block, and in doing so will restore the counting-in-and-out device at the right hand end of the block to the position which it previously occupied without, however, disturbing any of the signals which were previously set, so that the signals can be restored by the car which set the signals when said car passes out from the block. When the car over-runs the signal it causes the cylinder 47 to be advanced one step, as above described, and when this occurs the controlling circuit 39 is opened at the counting-in-and-out device. The determining relay 38 thus becomes deenergized and its armature falls, closing the contacts 37 in the ground connection 35. When the car backs off the block and passes onto the insulated rail section 10 the track relay restoring magnet 6 will be energized, thus closing the restoring circuit 20 at the contacts 21 and a current path will be established as follows:

Feed connection 140, restoring circuit 20, restoring magnet 22 to the ground connection 19. The restoring magnet 22 is then energized causing its armature to be raised thereby closing contacts 82, 83 and a circuit will then be established from the feed connection 12, through wire 9, contacts 82, wire 74, contacts 100, contact 37 (it being remembered that the determining relay 38 is deenergized because the controlling circuit 39 is open) ground connection 35 to the main ground connection 19. Since the restoring magnet 36 is in this ground connection it will be energized thereby turning the cylinder 48 one step and bringing it into the position relative to the cylinder 47 which it occupied before the car ran past the signal. It will thus be observed that the current path for the current which is used in canceling the registration made when a car over-runs the signal is located entirely at the end of the block where the over-run signal is situated and no current is used from the other end of the block which would restore the signal to "open block" condition.

I have shown the controlling circuit 39 as provided with two contacts 125 which are normally closed by a contact 126 carried by the restoring pawl 51, said contacts being 130

arranged so that when the restoring magnet 36 is energized to lift the pawl the controlling circuit 39 is opened at the contacts 125. I have also shown the terminal connection 99 as provided with two similar contacts 127 which are normally closed by the contact 128 carried by the setting pawl 50 so that when said setting pawl is energized the signal-actuating circuit will be opened at the 10 contact 128. These contacts are provided for opening the signal-setting and controlling circuits prior to the turning movement of the cylinders 47, 48 and thereby to prevent arcing as the contacts 61 and 58 pass 15 from one contact to another.

Under some conditions it might happen that after a car had over-run its signal both said car and the one which had previously entered the block and thereby set the signal 20 which was over-run would back out therefrom, and if under these conditions the car which set the signals backed out of the block before the other car which ran by the said signals, then it is desirable to provide means 25 whereby the signals will not be restored by the first car backing out and whereby the second car backing out will properly restore the signals. Under these conditions the car which backs out first would 30 restore its counting-in-and-out device to normal position and immediately the alternating relays would reverse so as to produce the same condition as would have existed if the over-running car had just entered an 35 unoccupied block. Then when said over-running car backed out of the block the signals would be restored to normal.

In case both cars should start backing 40 out of the block but the first car should clear the block while the over-running car was still on the insulated rail section 10, then the signal indications would become disarranged. To avoid this I have provided a mechanism which under these conditions 45 will prevent the ground connection 35 from being closed at the contacts 68 when the local relay 31 is deenergized. The mechanism for this purpose consists of a pivoted lever 131 carrying a bell crank lever 132 which is pivoted to one end thereof. This 50 lever 131 is interposed between the armature of the restoring relay 22 and the armature of the local relay 31 and is so arranged that when the restoring relay armature 22 drops it rocks the lever 131 thereby bringing the elbow lever 132 against the extension 133 of the local relay armature and lifting said 55 armature off from the contact 68, thus maintaining the ground connection 35 open.

60 It is essential to do this in order to prevent the restoring magnet 36 from being continuously magnetized and thus holding its pawl 51 elevated so as to prevent the restoring operation, for it will be readily seen 65 that when the first car backs out of the block

leaving the over-running car in the block the signal-actuating circuit would become connected with its ground connection 35 at the over-running end, thus energizing the magnet 36 and holding the pawl 51 elevated. 70 This, however, cannot happen if the ground connection 35 is open at the contact 68, as will be the case when the restoring relay 22 is deenergized.

If the power fails, then the current in the 75 signal-actuating circuit will fail and both of the local relays 31 will become deenergized, thus opening the local semaphore circuits and allowing the semaphores to fall to danger at both ends of the block. As soon as 80 the power is turned on again the signal-actuating circuit will become active, thus energizing the local relays 31 and closing the local semaphore circuits. The signals are 85 then brought to the safety position.

If the wires of the signal-actuating circuit 32 and of the controlling circuit 39 become crossed, then current will flow from the feed end of the signal-actuating circuit to the point where the wires are crossed and thence to the ground through both ends of the controlling circuit 39. The determining relays 38 will, therefore, both become energized, thus raising their armatures and closing the contacts 71, 72. Each pair of contacts 72 is 90 in a shunt circuit 110 connecting with the terminal connection 99 and shunting the local relay 31. Therefore, when the shunt circuits 110 are thus closed the local relays are short-circuited and become deenergized, thus opening the local semaphore circuits at 95 both ends of the block. The semaphores will thus both drop to danger. When the cross 100 is taken off from the circuits the proper conditions will be automatically restored.

I have above referred to the condition which would exist when a car over-runs its signal and enters a block already occupied by another car and then both cars back out of the block, the car which is legitimately 110 in the block clearing the block first. When the overrunning car enters the block and operates the counting-in-and-out device at its end of the block, the lever 88 will be actuated to close the contacts 92, and said 115 lever will be locked in this position by the locking latch 95. This is so because when the first car entered the block the signal at the overrunning end dropped into its horizontal position and thus left the locking 120 latch 95 ready to lock the lever 88 as soon as said lever was actuated.

In order to prevent the signals from becoming disarranged when the overrunning car backs out of the block, it is necessary to 125 provide means for releasing the locking latch 95 at the overrunning end of the block, and I have herein provided for this by making said locking member with an extension 116 having a latch 117 pivoted to its end, 130

which latch is in the path of movement of the end of the armature for the determining relay 38. In order to clearly illustrate the circuits they are shown diagrammatically 5 in the drawings, and the determining relay is shown as separated from the locking latch 95, but in practice these parts are so related to each other that the end of the determining relay armature will engage the latch 117 10 as said armature rises and falls. This latch 117 permits the armature to rise freely, but when the armature drops it engages the latch and the weight of the armature is sufficient to overbalance the locking latch 95 and raise 15 it. Therefore, when the overrun occurs and the determining relay is deenergized, it operates to prevent the locking latch 95 from engaging the lever 88.

I have herein shown at 118 a locking magnet 20 which is in the feed connection 34 for the signal-actuating circuit and the armature 113 of which has a locking extension 114 which when the magnet is energized engages a magnet 115 associated with the swinging 25 switch member 101. The purpose of this locking magnet is to lock the alternating relay in the position shown in Fig. 1 whenever a car enters the block from the left-hand end so as to prevent a car coming into the 30 block from the opposite end from reversing the relay and thus deranging the signal indication.

While I have shown herein one embodiment of my invention I do not wish to be 35 limited to the constructional features shown.

Having fully described my invention, what I claim as new and desire to secure by Letters Patent is:

1. In a block signal system, the combination 40 with a signal-actuating circuit extending the length of the block and provided at each end with a feed connection and a ground connection, of means normally connecting said circuit at one end to the feed 45 connection and at the other end to the ground connection whereby when no car is in the block said circuit is closed and current will flow therein, a normally-closed local semaphore circuit at each end of the 50 block which is separate from the signal-actuating circuit, means rendered operative by the current in the signal-actuating circuit when the latter is closed to maintain both said semaphore circuits closed, a signal 55 for each local semaphore circuit, means to hold each signal in "safety" position as long as its semaphore circuit is closed and to set said signal when said circuit is opened, and means rendered operative by a car entering 60 the block when the latter is unoccupied to connect both ends of said signal-actuating circuit to the ground and to maintain such connection as succeeding cars pass into the block and until all the cars have 65 passed out of the block.

2. In a block signal system, the combination with a signal-actuating circuit extending the length of the block and provided at each end with a feed connection and a ground connection, of means normally connecting said circuit at one end to the feed connection and at the other end to the ground connection whereby when no car is in the block said circuit is closed and current will flow therein, a normally-closed local semaphore circuit at each end of the block which is separate from the signal-actuating circuit, means rendered operative by the current in the signal-actuating circuit when the latter is closed to maintain both said semaphore circuits closed, a signal for each local semaphore circuit, means to hold each signal in "safety" position as long as its semaphore circuit is closed and to set said signal when said circuit is opened, and means rendered operative by a car entering the block from either direction when the latter is unoccupied to connect both ends of said signal-actuating circuit to the ground and to maintain such connection as succeeding cars pass into the block and until all the cars have passed out of the block. 70 80 85 90

3. In a block signal system, the combination with a signal actuating circuit extending the length of the block and provided at each end with a feed connection and a ground connection, a controlling circuit also extending the length of the block and provided at each end with a feed connection and a ground connection, means normally connecting the signal actuating circuit at one end of the block to its feed connection and at the other end to its ground connection and for connecting said controlling circuit at both ends of the block to its feed connection, a normally-closed local semaphore circuit at each end of the block, means operated by the current in the signal-actuating circuit when the latter is closed to maintain said local semaphore circuits closed, means operated by a car entering the block to connect one end of the controlling circuit to the ground and to deenergize the signal-actuating circuit thereby deenergizing the local semaphore circuits and causing the semaphores to be displayed and means operated by current in said controlling circuit to open the signal-actuating circuit. 105 110 115

4. In a block signal system, the combination with a signal-actuating circuit extending the length of the block and provided at each end with a feed connection and a ground connection, means normally connecting said circuit at one end to its feed connection and at the other end to its ground connection, a normally-closed local semaphore circuit at each end of the block, means rendered operative by the current in the signal-actuating circuit when the latter is closed to maintain the local semaphore cir- 120 125 130

- cuits closed, a signal in each local semaphore circuit rendered operative when the circuit is open, means to open the signal-actuating circuit when a car enters the block thereby 5 to set the signal, means to restore the signal when a car leaves the block, and means to prevent a car which overruns a signal set against it from restoring the signals when it backs out of the block.
10. 5. In a block signal system, the combination with a normally-active signal-actuating circuit extending the length of the block, of a normally-inactive controlling circuit extending the length of the block, a signal 15 at each end of the block, means to open the signal-actuating circuit and close the controlling circuit by a car entering the block, means to set the signals by opening of the signal-actuating circuit, signal-restoring 20 means, and means rendered operative by the combined action of the current in the controlling circuit when the latter is closed and said car leaving the block to actuate said restoring means.
25. 6. In a block signal system, the combination with a normally-active signal-actuating circuit extending the length of the block, of a normally-inactive controlling circuit extending the length of the block, a signal at 30 each end of the block, means to open the signal-actuating circuit and close the controlling circuit by a car entering the block, means to set the signals by opening of the signal-actuating circuit, signal-restoring 35 means and means to actuate the latter, and to restore the signal-actuating and controlling circuits to their normal conditions by the combined action of the current in the controlling circuit and said car leaving the 40 block.
7. In a block signal system, the combination with a normally-active signal-actuating circuit extending the length of the block, of a normally-inactive controlling circuit 45 extending the length of the block, a signal at each end of the block, means to open the signal-actuating circuit and close the controlling circuit by a car entering the block, means to set the signals by opening of the signal-actuating circuit, signal-restoring 50 means, means to actuate the latter by the combined action of the current in said closed controlling circuit and said car leaving the block, and means to prevent a disturbance 55 of the signals by a car entering the block at the opposite end while the first-named car is still in the block.
8. In a block signal system, the combination with a normally-active signal-actuating 60 circuit extending the length of the block, of a normally-inactive controlling circuit also extending the length of the block, a semaphore at each end of the block movable from a vertical to a horizontal position, a local semaphore circuit for each semaphore, 65 said semaphore circuits being separate from the signal-actuating circuit, means rendered operative by current in the signal-actuating circuit to hold the semaphore circuits normally closed, means operated by 70 current in the semaphore circuits to hold the semaphores in vertical position, means to render the signal-actuating circuit inactive and the controlling circuit active when a car enters the block, and means controlled 75 by the controlling circuit to arrest the movement of the semaphore at the entering end of the block in a midway position and means to cause said semaphore to give an indication when a second car follows the 80 first-named car into the block.
9. In a block signal system, the combination with a normally-active signal-actuating circuit extending the length of the block, of a normally-inactive controlling circuit also 85 extending the length of the block, a semaphore at each end of the block movable from a vertical to a horizontal position, a local semaphore circuit for each semaphore, 90 means rendered operative by current in the signal-actuating circuit to hold the semaphore circuits normally closed, means operated by current in the semaphore circuits to hold the semaphores in vertical position, 95 means to render the signal-actuating circuit inactive and the controlling circuit active when a car enters the block, means controlled by the controlling circuit to arrest the movement of the semaphore at the entering end of the block in a midway position, 100 and means to cause the last-named semaphore to have a momentary impulse when a second car follows the first-named car into the block while the latter is occupied by said first-named car. 105
10. In a block signal system, the combination with a signal-actuating circuit extending the length of the block and provided at each end with a feed connection and a ground connection, of means normally connecting said circuit at one end to the feed connection and at the other end to the ground connection whereby when the block is empty current will flow through said circuit, a local semaphore circuit at each end 110 of the block, each semaphore circuit being separate from the signal-actuating circuit, a switch for closing each local semaphore circuit, a magnet in the signal-actuating circuit which is normally energized by the current therein and when energized holds said 115 switch closed, a signal for each local semaphore circuit, means to hold each signal in "safety" position as long as its semaphore circuit is closed and to set said signal when 120 said circuit is opened, and means to connect both ends of the signal-actuating circuit with the ground when a car enters the block. 125

and to maintain such connection as succeeding cars pass into the block and until all the cars have passed out of the block.

11. In a block signal system, the combination with a signal-actuating circuit extending the length of the block and provided at each end with a feed connection and a ground connection, of means normally connecting said circuit at one end to the feed 5 connection and at the other end to the ground connection whereby when the block is empty current will flow through said circuit, a local semaphore circuit at each end of the block, each semaphore circuit being 10 separate from the signal-actuating circuit, a switch for closing each local semaphore circuit, a magnet in the signal-actuating circuit which is normally energized by the current therein and when energized holds said 15 switch closed, and a signal in each local semaphore circuit which is held inoperative by the current in said last-named circuit, and means to open the signal-actuating circuit and thereby open the local semaphore 20 circuits when a car enters the block at either end and to maintain said signal-actuating circuit open as succeeding cars follow the first-named car into the block and until all the cars have passed out of the block.
- 25 12. In a block signal system, the combination with a signal-actuating circuit extending the length of the block and provided at each end with a feed connection and a ground connection, of means normally connecting said circuit at one end to the feed 30 connection and at the other end to the ground connection whereby when the block is empty current will flow through said circuit, a local semaphore circuit at each end

of the block, each semaphore circuit being 40 separate from the signal-actuating circuit, a switch for closing each local semaphore circuit, a magnet in the signal-actuating circuit which is normally energized by the current therein and when energized holds said 45 switch closed, a signal in each local semaphore circuit which is held inoperative by the current in said last-named circuit, and means to open the signal-actuating circuit and thereby open the local semaphore 50 circuits when a car enters the block at either end and to maintain said signal-actuating circuit open as succeeding cars follow the first-named car into the block and until all the cars have passed out of the block. 55

13. In a block signal system, the combination with a normally-active signal-actuating circuit extending the length of the block, of a normally-inactive controlling circuit extending the length of the block, a signal at 60 each end of the block which is set by opening the signal-actuating circuit and is restored by closing said circuit, means to open the signal-actuating circuit and close the controlling circuit by a car entering the block, 65 means operated by current in the controlling circuit when closed to initiate the closing of the signal-actuating circuit, and means operated by a car leaving the block to complete the closing of said circuit whereby the 70 signals are restored.

In testimony whereof, I have signed my name to this specification in the presence of two subscribing witnesses.

JOHN J. RUDDICK.
